UNITED STATES PATENT OFFICE

FRIEDRICH POSPIECH, OF DRESDEN, GERMANY, ASSIGNOR TO CHEMISCHE FABRIK
POTT & CO., OF DRESDEN, GERMANY

PROCESS FOR PRODUCING SOLVENTS AND EMULSIFYING AGENTS

No Drawing. Application filed August 26, 1927, Serial No. 215,764, and in Germany February 25, 1926.

Numerous processes have already been proposed for the production of solvents and emulsifying agents for liquid and solid substances which are themselves insoluble in water, such as for instance oils, fats, mineral oils, hydrocarbons, waxes and the like.

In addition to the means such as soap and Turkey red oil, which have been used for some time, cyclohexanol or its homologues by themselves or in combination with hydrocarbons has been converted for instance for this purpose into a form soluble in water by means of soaps.

It has been found, that particularly good results are obtained, if aromatic or aliphatic alcohols, which are difficultly soluble or insoluble in water, are treated, either by themselves or in combination with hydrocarbons, with the alkali salts of aromatic or hydroaromatic hydrocarbon sulfonic acids or their derivatives as well as also with the corresponding free acids.

Benzyl alcohol and mixtures of benzyl alcohol with ordinary or chlorinated solvent naphtha have proved particularly suitable for the purpose in view.

Benzyl alcohol has a distinctive character as compared with the alcohols of high molecular weight, which are insoluble in water, such as cyclohexanol amyl alcohol terpene alcohols, since it possesses particular technical advantages, which make it especially suitable for the purpose in question.

The surprising discovery has been made, that it does not affect the frothing capacity of the preparations obtained. It is this fact in particular, which is of pre-eminent importance for cleansing and emulsifying agents. In addition however, benzyl alcohol has the advantage, that it has only a very slight odor. This fact is also important, because it is particularly desired in the industry to employ products which are as far as possible odorless, as it is difficult to eliminate such odors from the treated textile materials, and inconveniences are thus caused to those dealing therewith.

In this manner products are obtained, which can be used very effectively as solvents and emulsifying agents for fats of all kinds,

hydrocarbons, waxes and the like, as well as for the production of textile oils, boring oils, and as washing, cleansing and stain removing agents as well as for the most varied purposes in the textile and leather industry, as 55 wetting-out agents for dyeing and improving textiles and the like.

Examples

1. 15 parts of butyl naphthalene sulphonic acid are dissolved in 55 parts of water, and 28 parts of solvent naphtha are added thereto. The resulting emulsion is converted by means of 3 parts of normal butyl alcohol into a clear solution, which when mixed with 65 or poured into a considerable amount of water yields finely dispersed emulsions of the solvent.

2. 25 parts of the sodium salt of isopropyl-naphthalene sulphonic acid are dissolved in 61 parts of water and 14 parts of benzyl alcohol are gradually added. After passing through several non-homogeneous intermediary stages, a clear homogeneous liquid is finally obtained, which when diluted with a 75 considerable amount of water, yields clear solutions of benzyl alcohol, which are not even opalescent. As is well known benzyl alcohol dissolves very sparingly in water alone.

I claim:

1. As a new article of manufacture, an emulsifying agent comprising a clear aqueous dispersion of benzyl alcohol containing an alkali metal salt of isopropyl-naphthalene 85 sulfonic acid.

2. As a new article of manufacture, an emulsifying agent comprising a clear aqueous dispersion of benzyl alcohol containing an alkylated naphthalene sulfonic acid body. 90

3. As a new article of manufacture, an emulsifying agent comprising a clear aqueous dispersion of benzyl alcohol containing the sodium salt of isopropyl-naphthalene sulfonic acid in the proportion of about 14 parts 95 of benzyl alcohol to 25 parts of the sodium salt.

FRIEDRICH POSPIECH.
